(57) **CLAIM**

I claim the ornamental design for a compression force magnifier, as shown and described.

DESCRIPTION

FIG. 1 is a top perspective view of a compression force magnifier showing the new design;

FIG. 2 is a side perspective view thereof;

FIG. 3 is a side elevational thereof;

FIG. 4 is a front elevational view thereof; and,

FIG. 5 is a rear elevational view thereof.

The broken lines depict portions of the compression force magnifier that form no part of the claimed design.
